[57] **CLAIM**

The ornamental design for a shower filter, as shown.

DESCRIPTION

FIG. 1 is a top perspective view of a shower filter showing my new design, on an enlarged scale;

FIG. 2 is a bottom plan view thereof;

FIG. 3 is a rear elevational view thereof;

FIG. 4 is a front elevational view thereof;

FIG. 5 is a top plan view thereof;

FIG. 6 is a side elevational view thereof, the opposite side being a mirror image.
